(57) **CLAIM**

The ornamental design for a showerhead, as shown and described.

DESCRIPTION

In a preferred embodiment, the nature of this product is as a showerhead primarily useful for enabling a water spray from a ceiling or wall mounted fitting.

FIG. 1 is a bottom, front perspective view of a showerhead according to my new design;

FIG. 2 is a bottom plan view thereof;

FIG. 3 is a front elevational view thereof, the rear elevational view thereof being a mirror image of the front view shown;

FIG. 4 is a left side elevational view thereof, the right side elevational view thereof being a mirror image of the left side shown;

FIG. 5 is a top plan view thereof;

FIG. 6 is a top, left, front perspective view of a showerhead according to another embodiment of my new design;

FIG. 7 is a front elevational view thereof;

FIG. 8 is a left side elevational view thereof, the right side elevational view thereof being a mirror image of the left side shown; and,

FIG. 9 is a top plan view thereof.

The broken line representations of mounting structure in FIGS. 1, 3-9 and of outlet holes in FIGS. 1-2 and 6-7 are for the purpose of illustration only, and form no part of the claimed design.
